APPARATUS FOR RAISING LIQUIDS

James P. Stephens, Clarence M. Rader, Francis E. Steele, and William F. Flood, Oklahoma City, Okla., assignors to Phillips Petroleum Company, Bartlesville, Okla., a corporation of Delaware

Application April 29, 1935, Serial No. 18,906

9 Claims. (Cl. 103—234)

This invention relates to apparatus for raising liquids from wells, and in particular it relates to an improved type of gas lift pump for effecting raising of liquids, such as oil and water, from wells and drill holes.

The object of this invention is to provide an improved apparatus for raising liquids from wells, which contains a minimum of moving parts, and is positive and reliable in operation.

10 Other objects of this invention are to provide an apparatus for raising liquids from well and drill holes with a minimum amount of gas pressure and loss of volume thereof, and with a lower gas-liquid ratio than heretofore practical, and 15 without the necessity of intermittently releasing or bleeding all of the gas under pressure used in raising the liquid to the surface.

Still further objects and advantages of this invention will be appreciated and become more apparent upon a consideration of the following specification and the attached drawing, forming a part thereof, and wherein like reference characters designate like parts throughout the several views, and wherein,

25 Fig. 1 illustrates a vertical cross-sectional view of the apparatus for raising liquids,

Fig. 2 illustrates a modification thereof, and

Fig. 3 is a detailed modification of a valve which may be used in connection with the structures 30 shown in both Figs. 1 and 2.

Although this invention is adapted for raising various liquids from different types of wells and drill holes, one embodiment thereof will now be described in connection with recovering and raising liquids, such as oil and/or water from drill holes and wells. In order to describe one concrete embodiment of this invention there is shown in Fig. 1 a vertical cross-sectional fragmentary view of an oil well hole illustrating the improved 35 apparatus for raising liquids or the gas pressure lift pump, constituting one form of this invention, positioned therein. The well hole is shown as lined with the usual casing pipe 10 which extends to a depth 11, and below which is the bottom of the well hole 12, or the conventional shot hole, in which the liquids, such as water and oil, accumulate as they are forced therewith by the rock pressure or bottom hole pressure on the producing stratum 13.

40 A string of pipe or a tubing 14 extends down into the well hole and terminates at its lower end, adjacent the bottom of the well hole, in a bull plug 15, having the perforated slots 16, and through which the liquid is forced into the plug by the 45 bottom hole pressure. Above the bull plug the

tubing 14 is provided with two spaced plates 17 and 18 which form therebetween a chamber 19. The size of this chamber may vary with the different conditions encountered in the bottom of the well hole, but when a high bottom hole pressure is present a relatively large chamber 19 will be required to collect the liquid therein as will be later described. A valve cage 20 and seat 21 are secured to the upper side of plate 17, and are provided with the valve 22, to control the inlet 22' to chamber 19, and includes a valve stem 23 guided in the cage 20. A compressed spring 24 housed within the cage 20 serves to normally hold the valve 22 in a closed position, thus shutting off the chamber 19 from the bull plug 15 and the bottom of the well hole 12. Under certain conditions, as will be described later, the liquid in the bull plug 15 may be forced, by the bottom hole pressure, into the chamber 19, but may not flow out of the chamber back into the plug.

20 A second valve of any suitable type, which may be similar to the one described, is associated with plate 18 and includes a cage 30 and a seat 31 secured to the upper side of the plate and exteriorly of the chamber 19, and is provided with the valve 25 32 to control the outlet 32' for chamber 19, and includes a stem 33 guided in the cage 30. A compressed spring 34 serves to normally hold the valve 32 upon the seat 31, thus permitting flow of the liquid and gas, as will later be described, 30 in one direction only, namely from the chamber 19 to the space 34 above plate 18 between pipes 14 and 40. The valve seat 31 has a depending collar portion 35, and secured thereto is a pipe or tube 36 which extends into the chamber 19 to a 35 point adjacent the lower end thereof.

A second string of pipe or a tubing 40, which constitutes a fluid pressure or gas line, extends down into the well hole within the tubing 14. The lower end of the pipe 40 extends through an 40 aperture in plate 18 and establishes communication with the top portion of the chamber 19.

45 Inserted in the string of pipe 40, and a considerable distance above the chamber 19 and the valve 32, is a section of pipe 50 including the valve 50 seat 51 and a port 52 formed in a side wall of the pipe section below the seat and in which is secured a tube 53 spanning the space 54, between the pipes 40 and 14, and which fits into a port 55 formed in the tube 14, thereby establishing communication between the interior of tubing 40 and the space 56 between tubing 14 and the casing 10. Within the pipe 50 is a valve 57 provided with a stem 58, the upper end of which carries a head 59. Also within the pipe 50 and above the valve 55

seat 51 there is formed a stop 60 for the compressed spring 61, and which by forcing against the head 59 retains the valve 57 in contact with the seat 51. Upon the lower end of the valve stem 58 there is formed a head 62 having an orifice 63 and provided with the cylindrical sleeve or sliding valve 64 adapted to close port 52. Thus it will be seen that when the spring 61 is compressed, the valve 57 will be unseated and the sleeve 64 forced downwardly to close the port 52, and when the spring 61 seats valve 57 the sleeve 64 will be above port 52, leaving the same open. The valve 57, contained in the insert pipe 50, is positioned a considerable distance above the chamber 19 so that the liquid in the bottom of the well hole will not be likely to reach a level sufficiently high enough to choke the port 55, which is used as an exhaust and the full function of which will be described later.

20 In the operation of the gas lift pump above described the same is lowered into the well hole by means of pipes 14 and 40 until the bull plug 15 is adjacent the bottom of the hole 12, at which time the various parts will be in the positions illustrated in Fig. 1. With the gas lift pump in this position, the liquid forced out of the oil bearing strata 13 and into the bottom of the well hole 12 by the rock or bottom hole pressure will, along with any water present, enter through the apertures 16 into the bull plug 15, and as the liquid level and pressure therein builds up the liquid will be forced through inlet 22' and into the chamber 19 when the pressure is sufficient to overcome the force of spring 24 and open valve 22.

30 It is now apparent that chamber 19 will contain considerable liquid, such as water and/or oil, or may be completely filled with some liquid standing in the lower end of the pipe 40. A fluid under pressure, such as gas or air, is now supplied from the surface and forced down the pipe 40 and the pressure will be sufficient to compress the spring 61 and force the valve 57 open, and at the same time cause the sleeve valve 64 to close the port 52 which connects with the tube 53 and leads to the space 56 between pipes 10 and 14. The gas or air under pressure will continue on down pipe 40 and enter the chamber 19 building up therein a pressure sufficient to overcome the bottom hole pressure on the liquid in the bull plug 15 and to close valve 22, and so prevent the escape through the outlet 22', of the fluid under pressure and the liquid already contained in chamber 19 and to guard against the entrance of additional liquid. It is not only desirable to prevent the escape of fluid under pressure from chamber 19 so that the same may not be lost, but also to prevent it from getting into the well hole and forcing against the stratum 13 and so preventing the recovery of the oil therein. The pressure will continue to build up within the pipe 40 and chamber 19 and ultimately the liquid will be forced up into pipe 36 to open valve 32, against the action of spring 34 and the weight of any liquid which may be in pipe 14, and force the liquid through outlet 32'.

50 The oil will then be above the plate 18 in the space 54, and at this time the introduction of further air or gas under pressure through pipe 40 into chamber 19 is discontinued with the result that valves 57 will be forced to close by spring 61, and valve 32 will be closed by the action of spring 34 and the weight of any liquid in the pipe 14. This leaves the pipe 40, both above and below the valve 57, and the chamber 19 filled with air or gas under considerable pressure and which holds valve 22 closed, thus preventing the oil

which flows into the bottom of the well hole due to the bottom hole pressure, from entering the chamber 19. It rarely occurs in connection with the use of such a pump as here described that the bottom hole pressure builds up to the point where it will balance or overcome the air or gas pressure in chamber 19 and cause the oil to flow thereinto, therefore means are provided whereby the pressure in chamber 19 may be vented or bled to reduce or exhaust the pressure therein so as to allow the bottom hole pressure to again fill the chamber 19 with liquid. Means for doing this constitutes the sleeve valve 64, secured to valve stem 58, and which when the valve 57 is closed opens the port 52, thus allowing the air or gas under pressure in chamber 19 and in pipe 40 below the valve 57 to escape by port 52 through tube 53 into the space 56 and so reduce or exhaust the pressure in chamber 19 and yet maintain the volume of air or gas under pressure in pipe 40 above the valve 57.

With the pressure in chamber 19 now reduced or exhausted, the liquid by virtue of the bottom hole pressure, or the level thereof, will now be forced or raised up into the inlet 22' and enter chamber 19. Additional air or gas under pressure supplied by mechanical means controlled at the surface is then reintroduced into pipe 40, the pressure in which has not been materially exhausted or bled. From pipe 40 the air or gas under pressure is supplied to chamber 19 to again force the oil therefrom up into pipe 14. At such times air or gas is being applied through pipe 40 the valve 57 is open, due to the air or gas under pressure flowing downwardly therethrough, and the port 52 closed by the sleeve 54.

The above described operation is repeated at intervals as the air or gas under pressure is intermittently supplied through pipe 40, until, depending upon various well conditions, an appreciable column of liquid is built up in the space 54, between the pipes 14 and 40, at which time the air or gas pressure is then turned on and applied through pipe 40 as described for a time sufficient in length to lift the entire column of liquid in pipe 14 to the surface.

The above described operation of the apparatus for raising liquid constitutes a complete cycle of operation and is repeated at intervals, and in this manner the oil is forced to the surface in a most efficient and satisfactory manner.

In Fig. 2 there is illustrated a further embodiment of the present invention, and as the majority of the parts thereof are identical in both structure and operation with the embodiment illustrated in Fig. 1, only the essential parts thereof and the parts not present in Fig. 1 will be described in detail. In this embodiment there is present the conventional casing pipe 10, which extends to a depth 11. The bull plug 15, the valve 22, chamber 19, pipe 36, valve 32, and pipe 40 and their associated parts are, or may be, identical in both operation and structure with those illustrated in Fig. 1. It will be noted that in Fig. 2 there is present the casing pipe 10 and only one string of tubing, namely pipe 40, while in Fig. 1 there is utilized the casing pipe 10 and the two strings of tubing, 14 and 40. The insert 50 including the valve 57, stem 58, sleeve valve 64 and port 52 are substantially identical to the insert 50 and its associated parts as shown in Fig. 1 except the pipe 53 is dispensed with and one or more parts 52 communicate directly with a space 70 between the casing 10 and the string of tubing 40.

The bull plug 15 and the chamber 19 may be integral, or formed separately by any suitable members such as tubing or pipes, and then assembled. As illustrated, a packer body 88 is secured to, or integral with the upper end of the chamber 19 and if desired may include any suitable packing element 81, and an anchoring means 82. The lower end of pipe 48 has a screw threaded engagement with the neck 83 of packer 88. A pipe 48' constitutes an extension of pipe 48 and extends from the lower end thereof, where it has a packing fitting with neck 83, to and through plate 18 to connect chamber 19 with pipe 48.

The packer neck 83 is provided with a threaded portion 84 to facilitate removal of the fluid pressure lift pump in the event the string of tubing 48 should break, and also has formed therein a plurality of apertures 85 through which the liquid escapes into the space 78 after leaving chamber 19 through outlet 32.

The operation of this embodiment illustrated in Fig. 2 is substantially the same as that described in connection with the embodiment shown in Fig. 1, except that in the structure disclosed in Fig. 2 the entire device is lowered into the well hole by the single string of pipe 48, and when in place the packer 81 and anchor 82 are set and together they form a seal between the bottom of the well hole and the upper portion 78 thereof, and also serve to support the pump in the hole. Furthermore the ports 52, when not closed by the sleeve 64, are in direct communication with space 78 for bleeding or exhausting the pressure in chamber 19, the pipe 48', and the portion of pipe 48 below valve 51.

In Fig. 3 there is illustrated a modified type of valve which may be used to supplant the valve 51 as used in the structures shown in Figs. 1 and 2. This valve includes the pipe insert 98 and contains a valve seat 91, valve 92, and a stem 93 which is guided in the cage 94 and has a pointed end 95. A spring 96 within the cage normally tends to maintain the valve seated. The insert 98 is provided with the ports 99 which are connected by the transverse tube 97 in alignment therewith, and includes on its upper face an orifice 98 communicating with the internal bore of the tube and the ports 99. Formed integral with the valve seat 91 and cage 94, or secured thereto, there may be provided a yoke 100, which terminates in a screw threaded head 101 for facilitating the removal of the valve assembly for repairs or adjustments.

When the valve assembly above described is used to supplant the one shown in Figs. 1 and 2, and air or gas under pressure is being forced down the tubing 48 and through the insert 98, the valve 92 will be opened by the air or gas pressure against the action of spring 96. As the valve opens, the stem 93 is forced downwardly until the point 95 thereof seats in orifice 98, thereby preventing the escape of air or gas under pressure through the tube 97 and ports 99. When the pressure in the tubing 48 is decreased the valve 92 will be closed by spring 96, thus opening the orifice 98 allowing the pressure in the tube and chamber below to escape or bleed off through the orifice 98, tube 97 and port 99, so that the bottom hole pressure may again build up the liquid in the chamber as described with relation to the operation of the structure shown in Figs. 1 and 2.

It will now be appreciated that by applying air or gas under pressure to the pump above described in relatively short intermittent impulses that a considerable amount of liquid from the well hole

will soon be built up in the pipe above the liquid accumulating chamber without the necessity of bleeding or venting the air or gas under pressure in the entire string of pipe leading to the chamber, and that by then applying the air or gas under pressure to the chamber and allowing it to flow for a sufficient time all the liquid thereabove will be raised to the surface, thus effecting a material savings in the volume of gas or air needed to raise the liquid and reducing the gas-liquid ratio to a minimum.

What we claim as our invention is:

1. In a fluid pressure lift pump for raising liquids from the bottom of well holes to the surface including a chamber for the accumulation of the liquid, a pipe for introducing fluid under pressure into said chamber to force the liquid therein to the surface, the combination therewith of a valve in said pipe to control the introduction of fluid under pressure into said chamber, and a vent in said pipe to exhaust the fluid under pressure in said chamber without loss of fluid under pressure in said pipe, said vent comprising a tubular member extending transversely of and through said pipe, and having an orifice therein for the escape therethrough of fluid under pressure from said chamber and pipe, and means integral with said valve to open and close said orifice.

2. A fluid pressure operated device for raising liquids from well holes, the same comprising a tubing pipe extending into the well hole having formed integral therewith a liquid accumulation chamber provided with an inlet and an outlet, a second tubing pipe within and spaced from the first said tubing pipe and extending into said accumulation chamber for supplying fluid under pressure thereto, a valve in said pipe to control the introduction of fluid under pressure into said chamber, a vent tube extending from and connecting the interior of said second tubing pipe with the space exterior of said first tubing pipe for exhausting fluid under pressure from said chamber, and a closure for said vent tube formed integral with said valve and operable to open said vent when said valve is closed.

3. A fluid pressure operated device for raising liquids from well holes, the same comprising a tubing pipe extending into the well hole and supporting therefrom a liquid accumulation chamber of uniformly continuous diameter and of the same diameter as said pipe and having formed therein an inlet and an outlet, a second tubing pipe within and spaced from the first said tubing pipe and extending into said accumulation chamber for supplying fluid under pressure thereto, a valve in said pipe to control the introduction of fluid under pressure into said chamber, a vent tube extending from and connecting the interior of said second tubing pipe with the space exterior of said first tubing pipe for exhausting fluid under pressure from said chamber, and a closure for said vent tube formed integral with said valve and operable to open said vent tube when said valve is closed.

4. A fluid pressure operated device for raising liquids from well holes, the same comprising a liquid accumulation chamber having a uniformly continuous diameter, a tubing pipe extending into said chamber to support the same and to supply fluid under pressure thereto, a valve in said tubing pipe to control the admission of fluid under pressure, and a vent in said pipe for exhausting fluid under pressure from said chamber controlled by said valve.

5. A fluid pressure operated device for raising

liquids from a well hole to the surface, the same including a tubing pipe extending into the well hole, a tubular casing of uniformly continuous diameter suspended therefrom, spaced division plates transversely arranged in said casing and forming therebetween an accumulation chamber for liquid, a valve controlled inlet formed in the lower of said plates, a valve controlled outlet formed in the upper of said plates, a second tubing pipe extending to and for introducing fluid under pressure into said chamber, a pressure controlled valve in said tubing pipe positioned above said chamber for controlling the inlet thereto of fluid under pressure, an orifice in said tubing pipe below said last valve, an orifice in said first tubing pipe opposite said first mentioned orifice, and a pipe connecting said orifices for the escape therethrough of the fluid under pressure from said chamber when the application 20 of pressure thereto is discontinued.

6. A fluid pressure operated device for raising liquids from a well hole to the surface, the same including a tubular pipe extending into a well hole, a tubular casing of a uniformly continuous diameter suspended therefrom and of a larger diameter than said tubing pipe, spaced plates positioned in said casing to divide the same into an intermediate portion constituting a liquid accumulation chamber, an end portion forming a bull-plug, and another end portion constituting an outlet chamber, a valve controlled inlet in one of said plates, a valve controlled outlet in the other of said plates, said tubular pipe extending through said outlet chamber and into said liquid accumulation chamber for supplying fluid under pressure thereto, a valve in said tubing pipe to control the admission of fluid under pressure to said chamber, and a vent in said tubing pipe exterior of said accumulation chamber and a considerable distance thereabove for exhausting the fluid under pressure from said chamber when said tubing pipe valve is closed.

7. In a device for raising fluids from a well hole having a casing therein, a single tubing string extending into said well hole, an enlargement on the end of said tubing string providing a chamber, a packer positioned between said enlargement and said casing, spaced, division plates in said enlargement providing a liquid accumulation chamber therein, inlet and outlet valves in said plates, respectively, a conduit placing said tubing string in communication with said liquid accumulation chamber, a valve in said tubing string for controlling the admission of an actuating fluid under pressure to said chamber to force the accumulated fluid therefrom, said tubing string provided with a port for the exhaust of actuating fluid from said chamber, and a valve for controlling said exhaust port.

8. A fluid pressure operated device for raising liquids from well holes, the same comprising a liquid accumulation chamber, a tubing pipe extending into said chamber to support the same and to supply fluid under pressure thereto, a valve in said tubing pipe to control the admission of fluid under pressure, and a vent in said pipe for exhausting fluid under pressure from said chamber controlled by said valve.

9. A device for raising liquids from a well comprising a liquid accumulation chamber in said well hole having an inlet and an outlet for liquid, a tubing pipe connected with said chamber for supplying fluid under pressure thereto and exhausting fluid therefrom, a valve in said pipe for controlling the admission of said fluid under pressure to said chamber, said valve having a sleeve portion slidably engaging said tubing pipe, a vent in said tubing pipe adjacent said sleeve and adapted to be closed thereby in the fluid admitting position of said valve.
